UNITED STATES PATENT OFFICE.

FRANK E. FLEMING, OF DETROIT, MICHIGAN, ASSIGNOR TO THE UNDERFEED STOKER COMPANY OF AMERICA, OF DETROIT, MICHIGAN, A CORPORATION OF NEW JERSEY.

TUYÈRE BLOCK.

Application filed January 10, 1921. Serial No. 436,168.

To all whom it may concern:

Be it known that I, FRANK E. FLEMING, a citizen of the United States, residing at Detroit, in the county of Wayne and State 5 of Michigan, have invented certain new and useful Improvements in Tuyère Blocks, of which the following is a specification.

The retort-bordering tuyère blocks of underfeed stokers are commonly made in the 10 form of hollow-open bottomed castings, having top end front and rear walls in an integral structure, and when any portion of the wall that is exposed to fierce action of the heat burns out or becomes seriously damaged 15 the entire tuyère block has to be replaced. The front wall of the block (which faces toward the retort) has air passage openings or tuyères formed therein, and while it is ordinarily made thicker than the other walls 20 it is weakened by the perforations, is subject to intense heat, and so is especially subject to rapid deterioration both from burning and from clogging of its tuyères.

My invention provides a novel tuyère 25 block with a separable front wall, readily replaceable if damaged but firmly held in place under normal conditions, such block having, additionally, advantages in manufacture due to making easy the coring of the block-body and the casting of the apertured front wall.

In the drawings, Fig. 1 is a front elevation of the tuyère block in place, with a fragment of the retort flange in section; 30 Fig. 2 is a section on line 2—2 of Fig. 1; Fig. 3 is a rear view of the front plate; and Fig. 4 is a plan view, with parts broken away, of a series of blocks.

10 indicates in general a fragment of a 40 retort, from the side wall 11 of which there springs a horizontal flange 12 having made therein a series of block receptive openings 13. These orifices preferably have sloping side walls 14 giving each aperture a 45 downward taper, and they are arranged close to the inner face of the retort—separated therefrom by only a narrow horizontal lip 15,—and close together lengthwise of the retort, leaving narrow horizontal 50 bar surfaces 16 between them. Each tuyère block 18 of a length equal to distance between centers of the openings 13, may be of any ordinary superficial design but is novelly made up of two portions, the hol-

low body 19 and the front-wall plate 20. 55 The body comprises a base portion 21 downwardly tapered to fit in the opening 13 and a head portion 22 integrally connected with the base by a seat-forming shoulder 23 that will rest on the side and rear margins of an opening 13. The open bottomed base 21 is shown as spanned from front to rear by an integral yoke 25 through which, just below the retort-flange 12 a retaining rod 26 may be run to hold the aligning blocks in position. The front of the body 19 is left open, except preferably for a narrow front bar 27 forming part of the lower margin of the base, this bar affording an anchorage for one end of the yoke 25 and preferably having its top flat near its front edge but provided with a rib 28 along its rear edge. The top wall 29 of the head has a lug 30 cast thereon, adjacent the front opening and centrally of the length 75 of the block.

The front plate 20 has tuyères 31 made therethrough in suitable arrangement, preferably in the grid-form shown that leaves a central vertical bar 32 unperforated. Such 80 plate rests flat against the sloping front edges of the top and side walls of the head, has a horizontal bottom edge-portion 33 to seat smoothly on and cover the lip 15 of the retort and has a bottom fin or rib 34 shaped 85 to fit the front edge of opening 13 and extend into groove between the front wall of the opening 13 and the rib 28 on the cross-bar 27 of the base. On its rear face the front plate carries an upwardly reaching curved hook or finger 35 projecting from grid-bar 32 to engage with the central lug 30 of the body's top-wall.

In assembling the parts the front plate is hooked to the lug 30, with the bottom 95 margin of the plate resting on the flat part of bar 27 of the body base (the rib 34, thus placed, constituting an effective continuation of the base contour), and then the assembled block is dropped into its orifice 13 100 and secured by the tie-rod 26. Manifestly the parts so anchored cannot separate since the front plate is retained against outward displacement by the engagement of hook 35 and lug 30 at the top and by the engagement of its fin 34 in the opening 13 at the bottom. If the front plate burns through 105 or clogs, however, rod 26 may be removed

and the damaged tuyère block lifted out of position, whereupon substitution of a new front plate may be made.

It will be seen that the open-faced construction of the body and the separate formation of the front wall greatly facilitates casting of the parts.

While I have herein described in some detail a particular embodiment of my invention it will be apparent to those skilled in the art that changes in details of construction and arrangement may be made without departure from the spirit of my invention, within the scope of the appended claims.

15 I claim:

1. As an article of manufacture, a tuyère-block comprising a body portion having in an integral structure top, rear, and end walls and a base portion providing a front-bar, the front surfaces of said top, rear and end walls lying in a plane, and the top surface of said front-bar extending forwardly beyond said plane at an abrupt angle thereto; and an apertured front plate shaped at its side and top margins of its rear face to lie against the front surfaces of said side and end walls of the body, and shaped at its bottom edge to rest upon the top surface of said front bar, whereby to cover the open front face 30 of the body and to be placeable and removable from the front.

2. A tuyère-block comprising two separable portions, the one portion consisting of a body having an open front head and an open-bottomed base of smaller perimeter than the head, said base having a front bar

at its bottom and having an integral yoke extending between the said bar and the opposite wall of the base, the open front of said head having its surfaces lying in a plane 40 of generally upright direction and said front bar having its upper surface lying in an abrupt angle to said plane and extending in front of said plane; and the other portion of said block comprising an apertured front plate adapted and arranged to overlie the open front of said head and having a lip at its bottom to rest upon the front bar and shaped to continue the base contour, said plate having an outwardly curved hook near 45 its top and said head having a lug arranged to be engaged by said hook by a swinging movement of the front plate from the front of the structure.

3. The combination of a supporting structure arranged in generally horizontal position and having a generally vertical opening therethrough; and a tuyère block constructed to be seated in said opening and comprising an open front body portion and a removable front plate, said body portion providing a front bar arranged to lie within the aperture of the support below the top surface of the support and said front plate having a bottom lip extending within said aperture of the support and engaging said front bar, said front plate and said body having near the top thereof respectively an outwardly curved hook and a hook-receptive lug, substantially as and for the purposes described.

FRANK E. FLEMING.
